[57] ABSTRACT

Apparatus for loading a tube with amalgam or other pasty substance in which a plurality, preferably three, rollers are equiangularly spaced close together to define among them a central passageway, the apparatus having means for locating the tube to be filled below the passageway created by the rollers. The rollers are operable to roll a charge of amalgam into a roll having a diameter slightly less than that of the tube to be filled, whereupon the amalgam passes through the passageway and into the tube.

AMALGAM LOADER

This invention relates to a method and apparatus for loading amalgam into a tube which forms a part of the dental dispenser utilized by a dentist for filling teeth.

In U.S. Pat. No. 3,222,037, Thiel et al. have described apparatus for loading amalgam into a tube. The objective of the invention there as well as here is to minimize the handling of amalgam as much as possible and to reduce the contaminates to which the amalgam is exposed in the present practices of mixing and loading dispensers. Earlier inventors had noted the desirability of dispensing amalgam from a tube, but none had suggested a feasible way of getting amalgam into the tube. By its very nature, amalgam tends to be difficult to work with for it so easily compacts, thereby frustrating efforts to force amalgam into a tube through any conventional approach.

The invention of the Thiel et al patent provided a solution to the problem of loading amalgam into the tube, the invention utilizing a capsule with a tube mounted on one end of the capsule and a pestle for driving the amalgam out of the capsule into the tube. The capsule when mounted on an agitating device caused the amalgam to flow from the capsule into the tube. The invention of that patent has proved satisfactory in every respect insofar as the operation is concerned. However, present practices in dentists' offices give rise to a need for a different and perhaps more universal loading apparatus. For example, the throw-away capsules containing the amalgam constituents are very popular, particularly with the dental assistants who prefer them to reusable capsules which must be cleaned from time to time. Additionally, there are a wide amalgamators of amalgamators used in dentists' offices, and it might not seem economically feasible to add a combination amalgamator-loader to an office already having a satisfactory amalgamator.

It has therefore been an objective of the present invention to provide a loader for premixed amalgam, that is, amalgam which is mixed in any type of amalgamator including those amalgamators which employ disposable capsules.

To this end the invention contemplates the provision of a group of rollers inclined outwardly to provide a funnel, the lower extremities of the rollers defining a passageway through which a roll or stream of amalgam passes. A gob of amalgam disposed centrally of the rollers will, upon rotation of the rollers, be caused to take the shape of a roll having a very small diameter, that roll of amalgam being capable of sliding into a tube, thereby to load the tube.

As shown in Thiel et al. U.S. Pat. No. 3,221,409, one form of the dispenser tube is curvilinear. Loading such a curvilinear tube mounted immediately below the lower extremities of the rollers has proved difficult for the amalgam tends to become jammed before complete entry into the tube. It has therefore been another objective of the invention to provide for the filling of the curvilinear tube in the apparatus of the present invention by interposing a straight tube between the lower extremities of the rollers and the curved tube to be loaded. The straight tube forms a secondary passage permitting the roll of amalgam to be fully formed before it begins its movement into the curvilinear tube.

Another objective of the invention has been to improve the shape of the curvilinear tube to facilitate its

manufacture, loading and to tend to assure freedom from clogging in use. In this regard, the tube of the present invention is formed with its center axis forming an arc of a circle preferably on approximately a 1 inch radius. Further, the tube has a slight taper, being approximately 0.004 inch wider at its discharge end than at the opposite end.

In early models of the invention, it was found that on occasion the amalgam would simply rest among the rollers as they were rotating without becoming formed into an elongated roll suitable for introduction into the tube. To provide substantially complete reliability insofar as the performance of the apparatus is concerned, two features have been added. First, at least one of the 15 rolls, and preferably all of them, have had a plurality of dimples formed in their surface to provide a somewhat roughened surface whereby the rollers effectively work on the amalgam as they rotate. It has also been found that the reliability of the apparatus is improved if the 20 amalgam is in the form of a ball when it is introduced between the rollers. Therefore, as a further improvement into the invention, means are provided for rolling mixed amalgam into a ball before it is disposed between the rollers.

25 As a further feature of the invention, provision is made to receive a dispenser of the type to be filled by the invention, the tube of the dispenser being located immediately below the straight tube depending from the rollers. The receiver for the dispenser is provided with a switch which causes the automatic operation of the motor which drives the rollers, or alternatively to provide for the operation of the switch upon slight depressing of the dispenser.

30 Still another feature of the invention has been to provide guide fingers located between adjacent rollers, the guide fingers providing greater assurance of the confining of the amalgam to a location central of the rollers.

The several objectives and features of the invention will become more readily apparent from the following 35 detailed description taken in conjunction with the drawings in which:

40 FIG. 1 is a side elevational view partly in section of the apparatus;

45 FIG. 2 is a top plan view of the roller system taken along lines 2-2 of FIG. 1;

50 FIG. 3 is a cross sectional view through the straight tube and dispenser tube illustrating the physical and dimensional relationship;

55 FIG. 4 shows an alternative embodiment for loading a straight tube with an automatic switch;

60 FIG. 5 is a plan view of an alternative embodiment illustrating the use of guide fingers associated with the rollers; and

65 FIG. 6 is a diagrammatic view illustrating the use of a device for forming a ball of the amalgam before it is introduced between the rollers.

In FIG. 1 the loading apparatus is indicated generally at 10 and shown in position for loading a dispenser indicated at 11, the dispenser being generally of the form shown in Thiel et al. U.S. Pat. No. 3,221,409.

The loading apparatus includes a base 12, a column 13, the column 13 supporting a housing 14 which contains the rollers and associated apparatus. The housing 14 has a bottom wall 15 projecting out of the column 13.

Three rollers 18, approximately one-half inch in diameter, are rotatably mounted on a base 19 which is in

turn mounted on the bottom wall 15 of the housing. The rollers are rotatably mounted by means of three pins 21 fixed in the base 19. The pins are angled outwardly by an angle of approximately 2° to the vertical. The axes of the rollers are also inclined toward the side through an angle of approximately 4° . More specifically, the outward swing of the axis through 2° defines a plane. The sidewise swing through 4° is through a plane perpendicular to that first plane. The outward angulation creates the funnel relationship of the rollers. The sidewise angulation, coupled with the speed of rotation, causes the surface of the rollers to impart a downward component of force on the amalgam. For example, as each roller is viewed from the apex of the triangle which the three form, the roller leans to the left. When viewed from above, the rollers rotate counterclockwise. The rollers are simply slidably mounted on the pins, the axes of the rollers having the same angulation as the axes of the pins.

In the preferred embodiment, each roller is driven approximately 500 rpm, but this speed of rotation is subject to considerable variation without affecting anything except the speed with which the amalgam is formed into a roll and loaded. As illustrated in FIGS. 1 and 2, the rollers are driven by an endless belt 24 which passes around the group of rollers into contact with each of them and around a pulley 25. The pulley 25 is fixed to a shaft 26 carrying a larger pulley 27 around which a second belt 28 passes, the second belt passing around a drive shaft 29 of a motor 30. As shown in FIG. 2, the rollers have lower edges or extremities 32 which together define a passageway 33 through which a roll of amalgam, formed by the rollers, passes. The innermost points, indicated at 34, of the lower extremities of the rollers define an imaginary circle indicated by the dotted line 35 having a diameter A. The diameter A is the approximate diameter of the roll of amalgam as it passes through the passageway 33. That diameter preferably is a few thousandths of an inch smaller than the tube which it is to fill.

The housing has an outer wall 38 having an opening 39 in its upper surface, the opening 39 overlying the rollers 18. The wall has a molded taper indicated at 40 to guide a ball of amalgam to the opening 39 so that it will drop into the space formed among the three rollers.

As illustrated in FIG. 3, the base 19 and bottom wall 15 of the housing 14 have a hole 42 therethrough into which a straight tube 43 is mounted, the hole 42 and straight tube 43 being located immediately below the rollers 18 and coaxial with the imaginary circle 35 defined by the lower extremities of the rollers. The straight tube has a center passageway 45 of a diameter B slightly greater than the diameter of the imaginary circle 35 so that amalgam formed of the diameter A will pass easily through the straight tube passageway 45. The lower end of the tube 45 has a flared opening 46 to receive the discharge end 47 of a dispenser tube 48 which is to be loaded. The tube 48 has a tapered passageway 49 whose larger diameter C at the discharge end 47 is slightly greater than the diameter B of the straight tube passageway 45. The dispenser passageway 49 tapers down to a smaller diameter D at its inner end 50.

The dispenser tube 48 is curved, having a curvilinear axis 51 through the center of it, the axis being the arc of a 1 inch radius circle.

Satisfactory results have been achieved with the apparatus of the invention when the dimensional relationships are as follows, these relationships being set forth herein for example and not by way of limitation:

Diameter A — 0.095
Diameter B — 0.102
Diameter C — 0.104
Diameter D — 0.100

A dispenser receiver 55 is mounted below the housing 14 and has a seat 56 to receive the dispenser 11. The bottom of the seat is formed by a switch operator 57 pivoted at 58 to the receiver. The operator 57 has a wall 59 engageable with a microswitch 60 mounted in the receiver. It can be seen that mounting the dispenser 11 in the dispenser receiver, by first positioning the curved tube 48 in the flared socket 46 of the straight tube 43, causes a tube mounting collet 62 in the end of the dispenser to rest upon the operator 57. Depending upon the spring loading of either the microswitch or the operator 57, the positioning of the dispenser as shown will cause the switch to operate, or alternatively, a slight depression of the dispenser 11 will overcome the spring resistance of the microswitch or operator and cause the switch to operate. The microswitch 60 is connected at the circuit with the motor 30 so that closing of the microswitch causes the motor to run and the rollers to rotate.

As a feature of the invention, provision is made for forming amalgam into a generally spherical ball. As illustrated in FIG. 6, a ball-forming accessory 65 is mounted on the top of the housing having a discharge port 66 overlying the opening 39 at the top of the housing. The apparatus includes a block 68 having a circular groove 69 into which amalgam to be balled is dropped. A flexible wiper 70 is secured to an arm 71 rotatably mounted on an integral shaft 72 at the block 68. As the shaft 72 rotates, the wiper 70 revolves about the groove 69, pushing the amalgam ahead of it until a ball is formed. The shaft 72 is driven by the motor 30, the shaft 72 being connected by a coupling 73 to the shaft 26.

The block 68 has a valve 74 constituted by a plug 75 mounted in a transverse hole 76 forming a communication between the groove 69 and the opening 66. The plug 75 has a transverse hole 77 through it and a groove 78 in one surface of it, the groove 78 normally forming a continuation of the groove 69 when the plug is rotated to bring the groove to an upwardly facing position. It is in that attitude, as illustrated in FIG. 3, that the amalgam is formed into a ball. After the amalgam has been formed into a ball, the plug 75 is rotated through an angle of 90° to bring the hole 77 into a vertical attitude so that the ball drops through the hole and into the rollers.

As an alternative to the automatic ball former, the amalgam can be formed into a ball in a squeeze cloth frequently used in the preparation of amalgam.

A modification of the invention is illustrated in FIG. 4. There, when a straight tube is to be loaded, the straight tube 43 and dispenser receiver 55 can be eliminated. A straight tube is used, for example, with a dispenser packer of the type illustrated in Thiel et al. application, Ser. No. 198,185. In the modification of FIG. 4, the straight tube 80, with one end stoppered as at 81, is held immediately below the opening 42 through the housing bottom wall 15 and base 19. A flange on the collet or mounting end 82 of the straight tube 80 en-

gages a microswitch actuating lever 83, which actuates a microswitch 84 connected to the motor 30 to cause the operation of the motor when the tube is held in proper position. A flared ramp 85 may be employed to guide the tube 80 into position. In either embodiment, the tubes 48 or 80 may be disposable.

Another modification of the invention is illustrated in FIG. 5. There, a group of three guide fingers 86, depending from the top of the housing 14, projects between adjacent rolls 18 to provide additional assurance of the confining of the amalgam into central position between the rollers during the roll-forming operation.

While in the preferred form of the invention three generally vertical oriented rollers have been illustrated, it should be understood that the invention is not restricted to that configuration. For example, three conically shaped rollers could be employed, the cones having their bases located adjacent the base 19. The conical shaped rollers would obviate the need for outward canting of the cylindrical rollers.

Further, more than the three illustrated rollers could be employed as long as their grouping is such as to form a small enough passageway among them to reduce the glob of amalgam to a roll of a diameter suitable for insertion into the dispenser tube.

Still further, it would be possible to form the amalgam into a roll using only two rollers lying in a generally horizontal attitude, but this configuration would not be as convenient to use as the three vertically oriented rollers.

In the operation of the invention, including the modification of FIG. 6, the amalgam is first mixed in any one of the standard amalgamators. The mixed amalgam is disposed in the groove 69 of the ball former 65. A dispenser, previously positioned in the receiver 55, is depressed to actuate the microswitch 60 as described above. The energization of the motor 30 causes the rollers to rotate and causes the shaft 72 to rotate and the wiper 70 carried by it to revolve about the groove. As the wiper revolves about the groove, the amalgam is rolled into a ball. When the ball is formed, the plug 75 is rotated to bring the transverse hole 77 into communication with the groove 69, whereupon the ball drops in among the rollers 18. As the rollers continue to rotate for just a few additional seconds, approximately four in the preferred embodiment, the ball is formed into an elongated roll of amalgam which passes through the opening 42 in the base 19 and bottom wall 15 into the straight tube 43. Following passage through the straight tube 43, the roll slides into the dispenser tube 48, whereupon it is ready for deposit into a patient's tooth. It can be observed that throughout the whole operation there has been no requirement for the amalgam to touch the hands of a dental assistant and, hence, the possibility of contaminates, for example, moisture, from the dental assistant's hands is substantially eliminated.

I claim:

1. Apparatus for loading amalgam or the like into a tube comprising,
a support,
at least three rollers mounted generally vertically on
said support on equiangularly spaced axes,
the lower extremities of said rollers defining among
them a discharge passageway,
means for rotating said rollers,

and means for locating a tube to be filled below said discharge passageway.

2. Apparatus according to claim 1 in which the innermost points on the lower extremities of said rollers collectively define a circle of a diameter slightly less than the inside diameter of the tube to be filled.

3. Apparatus according to claim 1 in which the axes of said rollers are inclined outwardly toward their upper ends to enable said amalgam to be funneled downwardly.

4. Apparatus according to claim 3 in which the axes of said rollers are inclined sideways, said rollers being rotated in a direction to impart a downward component of force on the amalgam.

5. Apparatus according to claim 4 in which the outward angle of inclination is 2° and the sideways angle of inclination is approximately 4°.

6. Apparatus according to claim 1 further comprising,

a plurality of indentations formed on the surface of at least some of said rollers.

7. Apparatus according to claim 1 and a straight tube vertically mounted below said discharge passageway.

8. Apparatus according to claim 1 in which said rotating means comprises,

a belt passing about said rollers and means for driving said belt to rotate said rollers.

9. Apparatus according to claim 1 further comprising, means for rolling said amalgam into a ball prior to introducing said amalgam into said rollers.

10. Apparatus according to claim 1 wherein said support comprises a base,

a column projecting upwardly from said base,

a housing supported on said column,

a portion of said housing overhanging said base, said rollers being mounted in said overhanging portion,

a straight tube depending from said housing immediately below said rollers,

and a dispenser receiver mounted on said base below said tube to receive a dispenser having a curved tube whose end projects into said straight tube.

11. Apparatus according to claim 10 in which said rotating means comprises,

a motor in said housing drivably connected to said rollers,

a switch connected to said motor and mounted in said dispenser receiver for actuation by said dispenser when it is in position to receive amalgam.

12. Apparatus according to claim 10 in which said dispenser tube is curved, having an axis forming the arc of a circle.

13. Apparatus according to claim 12 in which said circle has approximately a one inch radius.

14. Apparatus according to claim 7 and a curved dispenser tube having one end located immediately below said straight tube, said dispenser tube having an axis forming the arc of a circle.

15. Apparatus according to claim 14 in which the inner points of the lower extremities of said rollers define a circle of approximately 0.095 inch,

said straight tube has an inside diameter of approximately 0.102 inch, and said curved tube has an inside diameter of approximately 0.104 inch.

16. Apparatus according to claim 15 in which the inside diameter of the end of said curved tube adjacent

said straight tube is approximately 0.104 inch, said tube tapering down to approximately 0.100 inch.

17. Apparatus according to claim 1 further comprising,

a housing surrounding said rollers and having an opening in the upper end to receive amalgam, means mounted on said housing for rolling amalgam into a ball, and valve means on said rolling means for releasing a ball of amalgam into said rollers.

18. Apparatus according to claim 17 in which said amalgam rolling means comprises a circular trough,

and a wiper mounted to revolve in said trough.

19. Apparatus according to claim 1 further comprising,

fingers mounted between respective rollers to confine amalgam centrally of said rollers.

20. Apparatus according to claim 1 further comprising,

three pins mounted on said support, said rollers being mounted on said pins, and said rotating means including an endless belt passing about said rollers to drive said rollers.

UNITED STATES PATENT OFFICE
CERTIFICATE OF CORRECTION

Patent No. 3,785,411

Dated January 15, 1974

Inventor(s) Ronald Lee Baker

It is certified that error appears in the above-identified patent
and that said Letters Patent are hereby corrected as shown below:

Column 1, line 34, delete "amalgamators" and insert

-- variety --

Column 1, line 35, "amalgamotors" should be

-- amalgamators --

Column 2, line 22, "into" should be -- to --.

Signed and sealed this 25th day of June 1974.
